(57) **CLAIM**

We claim the ornamental design for a beverage dispenser, as shown and described.

DESCRIPTION

FIG. 1 is an upper right side perspective view of the beverage dispenser of the present design;

FIG. 2 is an upper left side perspective view thereof;

FIG. 3 is a top plan view thereof;

FIG. 4 is a front elevational view thereof;

FIG. 5 is a left side elevational view thereof;

FIG. 6 is a rear elevational view thereof; and

FIG. 7 is a right side elevational view thereof; and,

FIG. 8 is a bottom plan view thereof.

Broken lines in FIGS. 1, 2, 4–8 are for illustrative purposes only and form no part of the claimed design.
